US0D1080640S

(12) **United States Design Patent** (10) Patent No.: **US D1,080,640 S**
Chen et al. (45) Date of Patent: ** Jun. 24, 2025

(54) **DISPLAY SCREEN OR PORTION THEREOF WITH GRAPHICAL USER INTERFACE**

(71) Applicant: **TOYOTA JIDOSHA KABUSHIKI KAISHA**, Toyota (JP)

(72) Inventors: **Xi Chen**, Nagoya (JP); **Kohei Morotomi**, Nagoya (JP)

(73) Assignee: **TOYOTA JIDOSHA KABUSHIKI KAISHA**, Toyota (JP)

(**) Term: **15 Years**

(21) Appl. No.: **29/798,750**

(22) Filed: **Jul. 9, 2021**

(30) **Foreign Application Priority Data**

Jan. 11, 2021 (JP) ..... 2021-000441 D

(51) **LOC (15) Cl.** **14-04**

(52) **U.S. Cl.**

USPC **D14/495**

(57) **CLAIM**

The ornamental design for a display screen or portion thereof with graphical user interface as shown and described.

DESCRIPTION

The sole FIGURE shows a front view of a display screen or portion thereof with graphical user interface showing the claimed design.

The peripheral dashed broken lines illustrate a display or portion thereof, and form no part of the claimed design.

1 Claim, 1 Drawing Sheet
